UNITED STATES PATENT OFFICE.

FOREST CHENEY, OF CHICAGO, ILLINOIS, ASSIGNOR TO CHENEY TALKING MACHINE COMPANY, OF CHICAGO, ILLINOIS, A CORPORATION OF ILLINOIS.

MOTOR FOR TALKING MACHINES.

1,421,404.

Specification of Letters Patent. Patented July 4, 1922.

Application filed January 18, 1919. Serial No. 271,776.

To all whom it may concern:

Be it known that I, FOREST CHENEY, a citizen of the United States, residing at Chicago, in the county of Cook and State 5 of Illinois, have invented certain new and useful Improvements in Motors for Talking Machines, of which the following is a specification.

My invention relates to talking machines 10 and particularly to spring motors therefor.

The present type of double spring motors is made with two separate spring barrels, one for each spring. These are mounted 15 with a single shaft extending through the center of the barrels and to which shaft one end of each of the springs is fastened, the other ends of the springs being secured to the barrels. Consequently, the initial winding and unwinding is accomplished through 20 the barrels and not through the shaft, the result being that a considerable amount of friction is developed in the springs themselves as they are being wound or unwound.

One of the objects of my invention is to provide a novel spring barrel for spring motors.

Another object is to provide a single barrel for double springs wherein both the 30 initial winding and unwinding is from the center of the springs.

A yet further object is to provide a two-part shaft for cooperation with a double spring arrangement whereby the initial 35 winding and unwinding may be through the shaft and the friction due to the springs largely eliminated.

A still further object is to provide novel 40 mountings for a motor-spring barrel whereby the same may be easily applied and removed and at all times properly aligned for cooperation with the other operative parts.

A still further object is to improve spring 45 motors for successful commercial use.

Generally speaking, I accomplish these 50 and other objects of my invention by providing a single barrel for double motor springs open at the top and bottom and having suitable covers therefor, and providing a two-part shaft with which the superimposed springs in the barrel are connected, one spring to each portion, the springs being arranged in reversely wound

relation with their outer ends removably secured to the spring barrel.

The objects above recited and other objects of my invention will be apparent to those skilled in the art from an inspection of the drawings, wherein,

Figure 1 is a side elevation of a motor 60 embodying my invention.

Figure 2 is a vertical section through the center of the spring barrel shown in Figure 1.

Figure 3 is a top plan view on the line 65 3—3 of Figure 2.

Figure 4 is a transverse section on the line 4—4 of Figure 2.

Figure 5 is a horizontal section on the line 5—5 of Figure 2, and

Figure 6 shows the preferred manner of 70 removably securing the springs to the spring barrel and shaft.

Referring to Figure 1, it will be noted that there is provided the usual motor frame 75 comprising top plate 10 and bottom plate 11 connected by the standards 12. 13 is the spring barrel mounted between the plates 10 and 11 so as to revolve about a vertical axis which manner of mounting will 80 be more fully described hereinafter. Connected to the shaft 42 below the bottom of the barrel 13 is a gear 14 meshing with a pinion 15 on shaft 16 which is held in vertical position between the plates 10 and 11. 85

On the same shaft 16 and below the gear 15 is a large gear 17 meshing with a small pinion 18 at the lower end of the turn table shaft 19. The shaft 19 extends above the top plate 10 and is adapted to extend 90

through a properly arranged aperture in the top casing of the talking machine for carrying the usual disc record turn table. Also secured on the shaft 19 is a gear 20 in mesh with a worm 21 on a horizontally 95 disposed shaft 22 which is maintained in bearings supported by lugs 23 and 24 extending downwardly from top plate 10. About the shaft 22 is mounted a fly ball governor comprising collar 25 which is secured to the 100 shaft in any suitable manner and another collar 26 adapted to rotate about and move along said shaft 22. Spring arms 27 connect the collars 25 and 26 in the usual manner and to each arm attached preferably 105 at an intermediate point is a weight 28.

Secured to the movable collar 26 is a flat disc 29 for cooperation with a brake shoe of a speed regulator of any well known type. For winding the motor there is provided 5 the usual winding shaft 31 carrying at its inner end a beveled gear 32 meshing with the bevel 33 on a stub shaft supported on the underside of the top plate 10 and on which shaft is a pinion 34 for meshing 10 with a gear 35 secured to the shaft 41 lying within and extending from the upper portion of barrel 13, as will be more fully explained hereinafter.

The spring barrel of my invention as before stated comprises a single member 13 made of pressed or cast metal and is open at the top and bottom and adapted to be closed by covers 36 and 37, removably held in position on the peripheries of the barrel 20 13 by set screws 38 or other suitable fastening means. Within the barrel 13 are mounted the reversely wound flat springs 39 and 40, detachably connected at their outer ends to the drum preferably at opposite points, 25 Figure 4 showing the arrangement of the winding of the spring 39 and Figure 5 showing the spring 40. Extending through the center of the spring barrel 13 is the two-part shaft comprising upper portion 41 and lower 30 portion 42, the adjacent ends of these portions being at preferably mid-position of the spring barrel. It is desirable that these shafts be maintained in alignment at all times. To accomplish this I provide the 35 lower end of the portion 41 with a counter bore 43 and the upper end of the portion 42 with a reduced extension 44 which projects into the counter bore 43 to maintain the portions 41 and 42 in axial alignment. The 40 inner end of the spring 39 is removably secured to the shaft portion 41 by the stud 45 and the inner end of the spring 40 to the portion 42 by similar fastening means 46, the outer ends of the springs being secured 45 to the spring barrel at 47 and 48 respectively, the connections at these points being such as to permit ready removal or application 50 of the springs and may consist of a slot 51 having an enlargement 52 for passing over the heads of the studs 45 which construction is illustrated in Figure 6. The outer ends of the shaft portions 41 and 42 project beyond the covers 36 and 37, of the spring barrel and are reduced as shown in 55 Figure 3 to form flat surfaces 49. For cooperation with the shafts outwardly of the covers of the spring barrels I provide the usual gears 14 and 35 which gears have slots formed therein of the same shape and size as 60 the reduced end portions 49 of the shafts 41 and 42, so that when the gears are applied thereto they will rotate with the shafts. As shown in Figure 2, I prefer to space the gears 14, 35, a slight distance from the covers 65 36 and 37, interposing between the covers

and the under sides of the gears washers 50. Threaded apertures 53 are formed in the outer ends of the shafts 41 and 42 for engagement with shouldered screws 54 having heads circular in transverse section. In the 70 top and bottom plates 10 and 11 of the motor case, I provide apertures 55 for the reception of the heads of the screws 54. To assemble the spring motor barrel in position in the frame the gears 14 and 35 are first 75 applied to the shouldered ends of the shafts 41, 42, as before described. The whole is then inserted in position between the bosses 56, 57 of the cover plates 11 and 10, respectively. The screws 54 are then inserted in 80 the openings 55 and screwed into the apertures 53 in the shaft portions whereby the spring barrel is brought into proper operative position with respect to the motor casing. These screws are tightened until the 85 gears 14, 35 are securely fastened to the shafts 41, 42, which is done by screwing home the screws so as to clamp the gears against the annular shoulders on the shafts. The washers 50 permit relative rotative 90 movement between the cover plates 36, 37 and the shafts 41, 42, and also support the drum between the gears, and engage shoulders on the shafts maintaining the shafts 95 concentrically relative to said gears and also render the drum oil tight. From the above it will be noted that I have provided a simple arrangement for securing the spring barrel in operative position in the motor casing and that such means assures at all 100 times proper aligning position of the spring barrel with respect to the operative parts so that there will be no likelihood of any play or other objectionable connection between the gears 14, 35, and the other gears with which these cooperate. Furthermore, to apply or remove the spring barrel it is necessary only to remove the two screws 54 then the spring barrel may be taken from its position as 105 shown in the drawings.

It will now be observed that the spring barrel of my invention is so arranged that operative connection is had between the springs 39, 40, and the train of gears driven through the gear 14, on the shaft portion 42.

Bearing in mind that the shaft members 41, 42, are relatively rotatable and also that these shaft portions are rotatable relatively to the covers 36, 37, the operation of the spring barrel will now be described. It 115 may be presumed that a record has been played and that the motor is unwound. The operation of the motor is stopped by application of the brake (not shown) to the record turn table. The operator then actuates 120 the winding shaft 31 through means of a handle, not shown, or by electric motor, if such is provided. Rotation of this shaft 31 through the train of gears shown, rotates the shaft portion 41 in a clockwise direction as 125 130

viewed in Figure 4, thus winding spring 39 from the inside. As the spring 39 is wound from the inside the tendency of the outer end is to unwind which will turn the spring 5 barrel 13 in clockwise direction. Consequently, the outer end of the spring 40 which is attached to the spring barrel casting but wound in a reverse direction to spring 39 will be wound from the outside 10 tending to unwind at the inside or tending to rotate the shaft portion 42 in a clockwise direction. However, the brake being applied to the turn table, shaft 42 will be prevented from rotation. It will thus be 15 observed that both springs 39, 40, are wound ready for actuation of the turn table and spindle 19 when the brake cooperating therewith is released. The springs now having been wound, and the shaft 31 locked 20 against rotation, and a new record having been applied, the brake, (not shown) cooperating with the turn table and the shaft 19 is released whereupon the shaft 42 will be rotated in clockwise direction by reason of 25 the fact that spring 40 is wound as before described, and unwinds from the inside while the outer end thereof turns the spring barrel 13 in a clockwise direction, which movement unwinds spring 39 from the outside 30 side. It will be observed that my invention provides that winding and unwinding of the springs that have to do with the operation of the disc record holder is from the center of the spring barrel through the shaft 35 portions 41, 42. Consequently, there is little friction created between the several turns of the springs within the barrel so that the entire unwinding force of the springs is utilized to drive the turn table and not to 40 overcome the friction experienced in the present type of spring motors.

By reason of the removable connection of the springs at the points 47, 48, of the spring barrel, and similar connections at the inner 45 ends with the shafts 41, 42, and the ready manner of removing the spring barrel from the motor casing, it will be observed that replacement of springs is but an easy matter. To replace either or both of the 50 springs it is necessary only to let the motor run down to the point where both springs are fully unwound whereupon the spring motor may be removed in the manner hereinbefore described, and either or both of the 55 cover plates taken off and the springs disconnected from the shafts as those may be removed from the barrel with the spring and also from the spring barrel. Referring to Figure 2 it will be noted that there 60 is interposed between the springs 39, 40, a horizontally arranged floating plate 58 which is rotatable with respect to either of the shafts 41 and 42. This plate is preferably perforated as shown at 59 in Figure 4 65 so that the lubricant within the spring bar-

rel 13 may be passed from the upper to the lower side or vice versa of this plate. This arrangement prevents gumming of the spring and consequent loss of the efficiency thereof.

While I have described more or less precisely the details of construction, I do not wish to be understood as limiting myself thereto, as I contemplate changes in form and the proportion of parts and the substitution of equivalents as circumstances may suggest or render expedient without departing from the spirit of my invention.

I claim:

1. In a spring motor, a spring barrel comprising a one-piece straight cylinder, a central support, a pair of springs in said cylinder, means for securing the outer ends of the springs to the cylinder, means for supporting the inner ends of the springs on said support, a one-piece head or end wall for each end of said cylinder, and means interposed between the two springs to divide the interior of said cylinder into two intercommunicating compartments, one for each spring, for housing and lubricating the springs thus separately inclosed, so that each of the two springs is wound and unwound in its own compartment.

2. A structure as specified in claim 1, said means for separating the two springs consisting of a plate or disk inserted in the cylinder.

3. A structure as specified in claim 1, said means for separating the two springs having a plurality of openings through which a lubricant can flow either way from one spring to the other during the operation of the motor.

4. A structure as specified in claim 1, said means for separating the two springs comprising a plate or disk loosely inserted in the cylinder and provided with openings through which a lubricant can flow from one compartment into the other.

5. In a spring motor, the combination of a pair of springs, means for housing said springs, and means for separating one spring from the other and providing means whereby a lubricant is forced back and forth from one spring to the other.

6. In a motor of the class described, in combination, a frame, a spring barrel, a shaft extending therethrough, and means engaging the shaft for removably securing said barrel in position in said frame, said means having bearings in the frame.

7. In a spring motor of the class described, in combination, a single spring barrel, two reversely wound springs therein in superimposed relation, a two-part floating shaft extending through said barrel, each portion extending substantially half-way of the barrel, the outer ends of said shaft adapted to support gears thereon and provided with

centrally disposed threaded apertures, set screws for engaging said apertures, and means for maintaining the inner ends of said portions in alignment.

5 8. In a motor of the class described, in combination, a frame, a spring barrel, a shaft extending therethrough, and means engaging the shaft for removably securing said barrel in position in said frame, said means 10 being removable from the outer face of the frame and having bearings in the frame.

9. In a motor of the class described, in combination, a frame, a spring barrel, a shaft extending therethrough, and means 15 engaging the shaft for removably securing said barrel in position in said frame, said means forming in effect removable extensions of the shaft.

10. In a motor of the class described, in combination, a frame, a spring barrel, a shaft extending therethrough, and means 20 engaging the shaft for removably securing said barrel in position in said frame, said means being rotatable with the shaft and 25 having bearings in the frame.

11. In a spring motor of the class described, in combination, a motor frame, a single spring barrel, two reversely wound springs therein in superimposed relation, a 30 floating shaft extending through said barrel, the outer ends of said shaft being provided with centrally disposed threaded apertures, and set screws for engaging said apertures, said set screws having bearings in the 35 motor frame.

12. In a spring motor of the class described, in combination, a motor frame, a single spring barrel, two reversely wound springs therein in superimposed relation, a 40 two-part floating shaft extending through said barrel, each portion extending substantially half-way of the barrel, the outer ends of said shaft adapted to support gears thereon and provided with centrally disposed

threaded apertures, and set screws for engaging said apertures, said set screws forming elongations of the shaft portions.

13. In a spring motor of the class described, in combination, a motor frame, a single spring barrel, two reversely wound 50 springs therein in superimposed relation, a two-part floating shaft extending through said barrel, each portion extending substantially half-way of the barrel, the outer ends of said shaft adapted to support gears 55 thereon and provided with centrally disposed threaded apertures, and screws for engaging said apertures, said screws forming elongations of the shaft portions and having bearings in the motor frame.

14. In a spring motor of the class described, in combination, a motor frame, a single spring barrel, two reversely wound springs therein in superimposed relation, a floating shaft extending through said barrel, the outer ends of said shaft adapted to support gears thereon and provided with centrally disposed threaded apertures, set 65 screws for engaging said apertures, said set screws being removable from the outer face 70 of the frame.

15. In a spring motor of the class described, in combination, a motor frame, a single spring barrel, two reversely wound 75 springs therein in superimposed relation, a two-part floating shaft extending through said barrel, each portion extending substantially half-way of the barrel, the outer ends of said shaft being provided with centrally disposed threaded apertures, and members 80 having screws for engaging said apertures, said members being removable from the outer face of the frame and when so removed serving to release the shaft portions from the frame.

Signed at Chicago, Illinois, this 13th day of January, 1919.

FOREST CHENEY.
